UNITED STATES PATENT OFFICE.

WILLIAM J. BOYNTON, OF SEATTLE, WASHINGTON.

SAW-SET.

No. 888,579.

Specification of Letters Patent.

Patented May 26, 1908.

Application filed April 26, 1906. Serial No. 313,847.

To all whom it may concern:

Be it known that I, WILLIAM J. BOYNTON, a citizen of the United States of America, and a resident of the city of Seattle, in the county 5 of King and State of Washington, have invented certain new and useful Improvements in Saw-Sets, of which the following is a specification.

The primary object of my invention is the 10 provision of a saw set which is simple in construction, embraces comparatively few parts, and is very efficient in operation.

With the above and other objects in view, to be referred to hereinafter, the invention 15 consists of the construction, arrangement and combinations of parts herein to be described and succinctly defined in the appended claims.

In the accompanying drawing, in which 20 like numerals of reference indicate like parts throughout the several views: Figure 1 is a view in perspective of my invention, portions of one of the gages being broken away. Fig. 2 is a view in top plan thereof with the 25 head, which carries the punches, removed, and Fig. 3 is a plan view of the said head inverted.

In carrying out my invention, I provide a 30 frame consisting of an anvil 1, which as now considered forms the base of the device, and an upright 2, the latter comprising parallel side portions between which the base is removably secured, as by bolts 3, or the like. The side portions of the upright are joined at 35 their upper ends by a cross piece 2' and provided at their lower end portions with outwardly projecting apertured lugs 4 through which bolts or the like can be passed for firmly securing the saw set to a suitable support.

Mounted over the anvil 1, is a head 5 carrying a plurality of punches, as 5' and 5" of different sizes for use in operating upon fine and coarse saw teeth respectively. As here- 45 in shown, the head 5 consists of a metal bar swingingly mounted between the side portions of upright 2 on a bolt 6 and having its opposite end portions each suitably formed to provide a respective one of said punches, 50 and said bolt is slidably engaged in suitable apertures provided in said bar and side portions or pieces of the upright so that it can be removed when desired to adjust the bar to present the required punch directly over the 55 active face, as 1' of the anvil. Head 5 is yieldingly held in retracted position rela-

tively to said active face of the anvil, by means of a flat spring 6' secured to the anvil and having its free end portion engaged with the forward end portion of the bar. 60

Reference numeral 7 indicates a rest for the saw, the same being pivoted to the anvil 1, as at 8, so that it may be given angular adjustment relatively to the active face of the anvil in conformity with the set it is desired 65 to impart to the saw teeth. The saw rest is provided with a slotted lug 9 through which a bolt 10, mounted in the anvil, projects and on the projecting screw threaded end portion of said bolt is a nut 9', the same when properly 70 adjusted pressing said lug firmly against the anvil and thereby securing the saw rest in its adjusted position.

Reference numeral 11 designates gages disposed at opposite sides of the active face 75 of anvil 1 and having shanks 12 adjustably secured each to its respective side surface of said anvil by means of clamping bolts 12', said bolts passing through the anvil and projecting through suitable slots in said shanks 80 so that the gages can be adjusted, in accordance with the length of the saw teeth to be operated upon, when said bolts are loosened.

The shanks 12 project above the anvil and embrace the head 5 so as to guide the same 85 and thereby insure alinement of the active punch with the saw tooth.

In operation, the saw rest 7 and the gages 11 are first properly adjusted, as heretofore described, and the saw then firmly held on 90 said rest with one of its teeth beneath punch 5' and the points of adjacent teeth resting against said gages. A blow is now delivered to head 5, above punch 5' so as to cause the latter to force the underlying saw tooth down 95 upon the active face of the anvil, thereby setting the tooth. Spring 6' now retracts the head and the saw is shifted to present another tooth for impact of the punch.

If it is desired to use punch 5", bolt 6 is re- 100 moved and the head 5 taken from the upright 2 and remounted therein in a reverse position, thereby bringing said punch directly over the active face of the anvil.

In the present construction, the active face 105 of anvil 1 is incorporated in a block 14 removably seated in a slot provided in said anvil and clamped between the shanks 12 which serve to prevent displacement of the block while permitting of its ready replacement when worn, by loosening bolts 12' and removing one of the shanks.

Various changes can be made in the details of construction without departing from the spirit of my invention, as defined in the appended claims, and, as is obvious if desired, 5 an anvil having an integral active face can be substituted for that herein shown.

Having thus fully described my invention, what I claim as new and desire to secure by Letters Patent of the United States, is:—

10 In a device of the type set forth, an upright of open form, an anvil secured therein, said upright having outwardly projecting

lugs on its lower portions, a head removably pivoted in said upright above said anvil and provided on its inner end portion with a 15 punch, and means for normally holding the inner end portion of said head elevated.

Signed at Seattle, Washington, this 17th day of April 1906.

WILLIAM J. BOYNTON.
